CLAIM

The ornamental design for the mobile support unit for a wire spool, as shown.

DESCRIPTION

FIG. 1 is a top, front isometric view of the mobile support unit for a wire spool;

FIG. 2 is a top plan thereof;

FIG. 3 is a side elevation thereof showing the side opposite FIG. 1;

FIG. 4 is a bottom plan thereof;

FIG. 5 is a front view thereof; and,

FIG. 6 is a rear view thereof.

The broken line showing of a rod is for illustrative purposes only and forms no part of the claimed design.

FIG. 1

FIG. 2

FIG. 3

FIG. 4

FIG. 5

FIG. 6
